F. J. F. LAUMONIER.

Circular Coke Oven.

No. 65,820.

Patented June 18, 1867.

United States Patent Office.

FREDERIC J. F. LAUMONIER, OF ANGERS, FRANCE.

Letters Patent No. 65,820, dated June 18, 1867.

IMPROVED CIRCULAR COKE-OVEN.

The Schedule referred to in these Letters Patent and making part of the same.

TO WHOM IT MAY CONCERN:

Be it known that I, FREDERIC JEAN FRANÇOIS LAUMONIER, of Angers, in the Empire of France, have invented certain new and useful improvements in Circular Coke-Ovens; and I hereby declare the following to be a full, clear, and exact description of the same, reference being had to the accompanying drawings.

The oven which is the subject of this application is circular, and divided into any suitable or desired number of radial compartments, converging towards a central chimney. Each radial compartment forms a conical oven, having but one door for charging and emptying it, which latter operation is effected by a movable engine or other suitable mechanism travelling upon a circular railway, so as to be brought successively before each door. The bottom of the oven slopes downward from the centre to the circumference in order to facilitate the operation of drawing out the material from the ovens. The sides or the lateral partitions between the compartments contain vertical flues, the mouths of which are located at the spring of the arch which forms the top of each compartment. These flues debouch into conduits running parallel with the bottom of the ovens, which conduct the flame to the head of the ovens. The flame and other products of combustion thence ascend through vertical flues, and finally reach the central chimney through a horizontal conduit situated on a level with the arch of the ovens. The heat generated in the ovens is thus caused to pass around their sides, bottoms, and ends; and each oven, besides its own heat, receives the heat of its neighbors. In the centre of the arch of each oven a feed opening is formed, and a circular railway, laid upon the top of the ovens, passes over these openings. The coal is supplied to the compartments by wagons with movable bottoms, which travel on the railway. They are moved until they stand over the desired feed openings, and then, their bottoms being removed or drawn aside, the coal pours into the compartments down through the feed openings. Around the space in front of the doors of the compartments, which contains the coke drawn from the said compartments, is another railway traversed by a small portable engine for emptying the ovens. It draws out the coke by means of a chain and iron rake introduced into the oven before the charging of the same. A tube or pipe, which encircles the oven, conducts water from a reservoir placed about seven metres above the ground, and can be discharged upon the coke, so as to extinguish the heat and flame, from any suitable number of nozzles placed or distributed upon the circumference of the circular tube at the requisite distance apart. This radial arrangement of the ovens around a central chimney prevents the excessive cooling or chilling of the mass of carbon; and, while the heat is thus rendered more steady and uniform, the oven may be constructed so as to be very solid and firm, and the whole management of the oven is simplified and made less laborious.

My invention will be readily comprehended by reference to the accompanying drawings, in which—

Figure 1 is a sectional elevation of the circular oven.

Figure 2 is a horizontal section of half of the oven.

Figure 3 is a transverse vertical section taken at the entrance to the compartments.

Figure 4 is a front elevation of one of the doors, together with the braces by which it is surrounded.

Figure 5 is a horizontal section at the entrance to one of the compartments.

Figures 6 and 7 represent a rake or shovel for drawing out the coke.

Figure 8 represents a crossing and turn-table on the circular railway.

Each compartment has its own system of flues, a^1 and a^2 , b , and b' , which flues have no communication with those of the other compartments. This arrangement admits of regulating the draught of each compartment at pleasure after the coal is filled in, and of proceeding to discharge the coke from each, after it has been carbonized, without interfering with the progress of the operation in the others. In the construction of the oven I make use of bricks of special forms. Thus, those which constitute the sides of the sloping flues a^1 and a^2 , and serve to support the flag or hearth-stones c , admit of these flues being prolonged to about 0^m.25 from the bottom or lower part of the oven. The stones c are placed symmetrically two by two. They are united together, in the direction of the length of the furnace, by a rebate or lapping piece, three centimetres in width, and of half the thickness of the bricks. This method of setting the flag-stones together prevents any communication between the chamber of the oven and the inclined flues under the bottom. These flues are separated from the vertical flues by brick piers at regular intervals apart. The conduits b' , which, in conjunction with the vertical flues b , put the ovens in communication with the central chimney C , are likewise formed of several layers of

brick of suitable dimensions and form, in order to fit upon the interior part D of the furnace, on which the whole structure rests.

The advantages obtained by the employment of brick of the forms above mentioned are as follows: Refractory or fire-bricks being bad conductors of heat, it therefore becomes necessary to reduce the thickness of the partitions between the ovens and their flues as much as possible without detracting from the solidity and durability of the partition walls, and, consequently, of the oven. Each brick, having the form and dimensions required in order that it shall fit in its place, is used without being cut or clipped, and thus preserves its strength, and enables me to reduce the thickness of the inclined and vertical partition walls to 0^m.08 for the one, and 0^m.10 to .11 for the other, at the same time preserving the strength of the oven unimpaired. Furthermore, there results from this reduction in the thickness of the partitions an increase in the diameter of the flues. The gases which are evolved by the combustion of the coal circulate more slowly, have more time in which to become inflamed, and the heat which they produce is more completely utilized; consequently, the combustion of the coal is more rapid, and the coke of better quality; the work of putting up the masonry is accomplished more rapidly and easily, and the cost of labor is considerably reduced. The charging of the ovens is effected through the top by means of openings d, which are furnished with cast-iron plates set into recesses or grooves formed in the masonry. These plates are united together, or placed one upon the other, in such manner as to form a double circular crown, and are each cast with four supports or chairs, in which are held the rails F, upon which move the wagons containing the coal for charging the ovens. The front of each oven or compartment is closed by a cast-iron door coated on the inside with refractory clay to protect it against the direct action of the heat. As these doors should not be opened unless to discharge the coke, they are provided near the top with openings closed themselves by smaller doors h, which allow the operator or attendant to inspect the work, and to see that the operation is conducted properly. Strong open-work ribbed plates E, of cast iron, are applied on the exterior of the ovens, to the mason-work partitions between them, so as to strengthen them. These plates are united together and connected by iron bolts and nuts i; and, besides bracing the oven, they serve to receive the hinges of the large doors, which are jointed or pivoted to them by means of iron rods or pins. Near the exterior edge of the space into which the coke is discharged from the ovens is a circular water conduit, composed of iron tubes, which communicates, by means of a branch pipe, with a reservoir of water placed six or seven metres above ground, and near the point where the steam engine of the grinding or crushing and coal-washing machines, if there be any, is located. Vertical ajutages B, provided with stop-cocks, are placed at equal distances apart; and there are also mounted on the conduit joints intended to receive copper or gutta-percha tubes, having mouth-pieces or nozzles, through which the water can be discharged upon the coke, and thus check its combustion at any time, either before or after it is drawn out from the ovens. A circular railway, F, concentric with the oven, or, rather, group of ovens, is located at the lowest point of the inclined or sloping space surrounding the oven. Upon this railway moves the apparatus L for emptying the ovens of the coke. Fig. 8 represents in plan a turn-table, F', and the relative position of the rails F and switches at the crossing or intersection of two tracks belonging to two groups of ovens A and A'. The turn-table F' serves, in this case, to transfer the apparatus L from one track to the other, so that the same apparatus may be used for two, or even more, groups of ovens. The rake or shovel for drawing out the coke is shown in figs. 6 and 7. This instrument is placed on the bottom of the furnace, the handle or knob turned towards the door, before the oven is charged with coal. The rake serves, after the coke is formed, to withdraw the mass, in a single piece, from the oven. This is effected by attaching, by means of a forked hook, the end of a traction-chain wound on the cylinder or drum of the apparatus L to the knob m of the rake, which is then drawn out from the oven by rotating the winding-cylinder.

Having described my invention, what I claim, and desire to secure by Letters Patent, is—

1. A circular coke-oven, composed of any suitable number of radial compartments converging towards a central chimney, substantially as herein described.
2. The combination, with the radial compartments of a circular coke-oven, as described, of the flues for conducting the products of combustion from the said compartments to the central chimney under the arrangement herein shown and specified.
3. The combination, with the radial compartments provided with openings in their top, of the circular railway passing over the said openings, as and for the purposes set forth.
4. The application and use, in connection with the herein-described coke-oven, of the water conduit or pipe encircling the same, substantially as and for the purposes herein specified.

In testimony whereof I have signed my name to this specification before two subscribing witnesses.

FRIC. LAUMONIER.
